UNITED STATES PATENT OFFICE

100,183

DESIGN FOR A COMBINED STEP PLATE AND SIGNAL CASING

Frederick G. Thwaits, Wauwatosa, Wis., assignor
to The Heil Co., Milwaukee, Wis., a corporation
of Wisconsin

Application December 28, 1934, Serial No. 54,622

Term of patent 14 years

To all whom it may concern:

Be it known that I, Frederick G. Thwaits, a citizen of the United States, residing at Wauwatosa, in the county of Milwaukee and State of Wisconsin, have invented a new, original, and ornamental Design for a Combined Step Plate and Signal Casing, of which the following is a description, reference being had to the accompanying drawing forming part thereof.

In the drawing:

Fig. 1 is a side elevation of a combined step plate and signal casing showing my new design;

Fig. 2 is a top view of the design of Fig. 1; and

Fig. 3 is a rear view of the combined step plate and signal casing of Figs. 1 and 2.

The important features of the new design, are the step plate, and a casing for the reception of a signal disposed beneath the plate, the combined fixture being especially adapted for location at an end of a vehicle.

I claim:

The ornamental design for a combined step plate and signal casing, substantially as shown and described.

FREDERICK G. THWAITS.
